[57] CLAIM

The ornamental design for a fender holder, as shown and described.

DESCRIPTION

FIG. 1 is a top plan view of the fender holder showing our new design;

FIG. 2 is a front elevational view thereof;

FIG. 3 is a rear view thereof;

FIG. 4 is a bottom plan view thereof;

FIG. 5 is a right side elevational view thereof;
FIG. 6 is a top, front, left side perspective view thereof with the outline of a rail and a buoy shown in broken lines;

FIG. 7 is a top, front, right side perspective view of another embodiment of the fender holder showing our new design, with the outline of a rail and a buoy shown in broken lines; and,

FIG. 8 is a top, front, left side perspective view of yet another embodiment of the fender holder showing our new design, with the outline of a rail and a buoy shown in broken lines.

The broken line showing of environmental association structure in FIGS. 6, 7 and 8 is for illustrative purposes only and forms no part of the claimed design.
